DISPLAY STAND

Lester V. Molenaar, Box 777—West Highway 40,
Willmar, Minn. 56201

Filed May 6, 1974, Ser. No. 467,493

Term of patent 14 years

Int. Cl. D20—02

U.S. Cl. D6—23

FIG. 1

FIG. 2

FIG. 3

FIG. 4

FIG. 5

FIG. 6

FIG. 7

FIG. 8

FIG. 9

FIG. 1 is a side elevational view of the display stand showing my new design;

FIG. 2 is a top view of FIG. 1;

FIG. 3 is a bottom view of FIG. 1;

FIG. 4 is a sectional view taken along 4—4 of FIG. 1;

FIG. 5 is a plan view of one of the spider elements of FIG. 1 on an enlarged scale and shown removed from the upright for convenience of illustration;

FIG. 6 is a bottom view of FIG. 5;

FIG. 7 is a side elevational view of the bottom side of FIG. 5;

FIG. 8 is an enlarged sectional view taken along line 8—8 of FIG. 5; and

FIG. 9 is an enlarged sectional view taken along line 9—9 of FIG. 5.

I claim:

The ornamental design for a display stand, substantially as shown and described.
